CLAIM

The ornamental design for a printer stand, as shown and described.

DESCRIPTION

FIG. 1 is a front, right, top perspective view of the printer stand in the first state, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, top perspective view of the printer stand in the second state;

FIG. 10 is a front, right, top perspective view of the printer stand in a detached state;

FIG. 11 is an enlarged view of detail 11 in FIG. 1;

FIG. 12 is an enlarged view of detail 12 in FIG. 1;

FIG. 13 is an enlarged view of detail 13 in FIG. 2;

FIG. 14 is an enlarged view of detail 14 in FIG. 6; and,

FIG. 15 is an enlarged view of detail 15 in FIG. 10.

The dashed broken lines illustrate portions of the printer stand which form no part of the claimed design.

The dash-dot-dash broken lines are for notating enlarged views and form no part of the claimed design.

1 Claim, 15 Drawing Sheets
